UNITED STATES PATENT OFFICE.

JAMES C. GLEED, OF NORTH YAKIMA, WASHINGTON.

ROTARY PUMP.

1,243,060.

Specification of Letters Patent.

Patented Oct. 16, 1917.

Application filed February 20, 1917. Serial No. 149,861.

To all whom it may concern:

Be it known that I, JAMES C. GLEED, a citizen of the United States, residing at North Yakima, in the county of Yakima and State of Washington, have invented certain new and useful Improvements in Rotary Pumps, of which the following is a specification, reference being had to the accompanying drawings.

10 This invention relates to certain improvements in rotary pumps and has relation more particularly to a device of this general character wherein radially movable blades are carried by a rotor and wherein said 15 blades coat with a hub eccentrically positioned relative to the rotor for imparting requisite movement to the blades; and it is an object of the invention to provide a novel and improved device of this general character wherein the hub is readily removable and can be replaced when required by the 20 necessities of practice.

It is also an object of the invention to provide a novel and improved device of this 25 general character wherein the stator includes a removable side plate and wherein said removable side plate coacts with the rotor to afford a support therefor.

A still further object of the invention is 30 to provide a rotary pump of this general character having novel and improved means wherein the parts subject to wear may be readily replaced whereby the life of the pump may be materially prolonged.

35 The invention consists in the details of construction and in the combination and arrangement of the several parts of my improved pump whereby certain important advantages are attained and the device is 40 rendered simpler, less expensive and otherwise more convenient and advantageous for use, all as will be hereinafter more fully set forth.

The novel features of the invention will 45 hereinafter be definitely claimed.

In order that my invention may be the better understood, I will now proceed to describe the same with reference to the accompanying drawings, wherein—

50 Figure 1 is a vertical sectional view taken through a pump constructed in accordance with an embodiment of my invention and at right angles to the axis of the rotor;

55 Fig. 2 is a transverse vertical sectional view taken through my improved pump as herein embodied;

Fig. 3 is a side elevational view of my improved pump with a side plate removed and with the shaft of the rotor shown in section;

60

Fig. 4 is a view in elevation of the inner face of the removable side plate as herein disclosed;

65

Fig. 5 is a view in end elevation of the removable hub as herein embodied; and

65

Fig. 6 is a longitudinal vertical sectional view taken through Fig. 5.

As herein embodied, S denotes the stator of my improved pump and which includes a casing 1 affording a substantially circular 70 chamber having in communication therewith at the upper portion of the casing the induction and eduction ports 2.

A side face of the casing 1 is open and said open side face is adapted to be closed 75 by the removable side plate or head P. Depending from the casing 1 are the supporting legs 3 of any ordinary or preferred type and for a purpose which is believed to be clearly apparent to those skilled in the art 80 to which my invention appertains.

Disposed transversely through the casing 1 above but in vertical alinement with the axial center of the chamber within the casing, is the shaft 4 also adapted to be disposed through the removable plate or head P when my improved pump is assembled, and said shaft 4 extends beyond opposite sides of the casing 1 and is adapted to be driven from any suitable source of power 90 coupled with either of the extended portions of the shaft.

The fixed side plate or head 5 of the casing 1 is provided with a depressed portion 6, the peripheral wall of which being concentric to the shaft 4 and the removable plate or head P is provided in its inner face with the depressed portion 7 of the same diameter as the depressed portion 6 and also concentric to the shaft 4 when said plate or 100 head P is in applied position.

Arranged within the casing 1 is a hollow rotor R having a side portion seated within the tapered portion 6 of the stator S and which is provided with the hub 8 keyed or 105 otherwise secured to the shaft 4, as indicated at 9. The side of the rotor R adjacent the open side of the stator S is also open and adapted to be closed by the removable head or plate P', and the central portion of the 110 plate or head P' is provided with an enlarged opening 10 into which extends the

inwardly directed annular flange 11 carried by the plate or head P and which is concentric to the shaft 4. The plate or head P' of the rotor R is provided with an outstanding annular flange 12 concentrically arranged relatively to the flange 11 hereinbefore referred to but spaced therefrom a predetermined distance.

Interposed between the flanges 11 and 12 are the anti-friction members 14 of any ordinary or preferred type but which are herein disclosed as roller bearings suitably mounted within the retaining rings 15. It will be at once self-evident that the flanges 11 and 12 together with the interposed anti-friction members 14 afford an additional support for the rotor R and whereby the same may be permitted to rotate with a minimum of frictional resistance. It is also to be noted as particularly illustrated in Fig. 2, that in order that the flanges 11 and 12 may have increased bearing surfaces the plate P is further depressed, as indicated at 16.

25 The periphery of the rotor R is provided with the transverse openings or slots 17 herein disclosed as four in number and equidistantly spaced, and slidably through each of said slots 17 is a blade B. Each pair of 30 opposed blades B is provided at one side portion thereof with an inwardly directed shank or extension 18 which is adapted to be received between the spaced ears 19 carried by the central portion of the sides of 35 an elongated yoke 20. The extensions or shanks 18 of the blades are detachably held to the ears 19 through the medium of the removable members 21 whereby it will be at once self-evident that the blades B may be 40 readily removed and replaced when the requirements of practice may so necessitate.

Disposed through the yokes 20 is the stationary cam member 22 with which the intermediate portions of the yokes 20 are 45 adapted to contact, and as is clearly illustrated in Figs. 1, 2 and 3, it is to be noted that the portions of the yoke coacting with the cam 22 are provided with the lining 50 blades 23 which directly contact with the periphery of the cam 22. These plates 23 are adapted to be removed as clearly disclosed in Fig. 2 so that upon a plate becoming unduly worn the same may be readily and conveniently replaced so that the life 55 of the pump is materially prolonged.

The cam 22 as hereinbefore referred to is tubular and the shaft 4 extends therethrough and as is clearly illustrated in the accompanying drawings, the cam member 22 is 60 cylindrical in form and arranged eccentrically to the shaft 4. One end of the cam 22 is closed, as indicated at 24, with the exception of the opening 25 through which the shaft 4 is disclosed. The closed end of the 65 cam 22 is provided with an arcuate shoulder

26 which is continued by the arcuate flange 27 whereby an annular shoulder is afforded and which is adapted to be seated within the annular recess 28 formed in the inner wall of the free end portion of the flange 11 hereinbefore referred to. The closed end 24 and the flange 27 of the cam member 22 are provided with the openings 29 and through which are disposed the headed members 30 which are in threaded engagement with the 75 removable plate or head P whereby it will be at once self-evident that upon removal of the plate or head P the cam member 22 will also be withdrawn. By this arrangement the cam 22 may be readily replaced when the requirements of practice may necessitate and without the necessity of disassembling the entire pump.

It has also been found of particular advantage to secure to the under surface of the 85 peripheral wall of the rotor R at opposite sides of each of the slots 17 the steel plates 31 continued or otherwise held in applied position but which are adapted to be readily removed and replaced. These plates 31 serve 90 to take up wear whereby it will be at once perceived that the life of the pump is further prolonged.

It is preferred that the blades B be made of tempered steel but by the use of the wear 95 plates 31 it will be at once self-evident that particular care need not be exercised in the character of metal from which the rotor R is produced. This is also true of the yokes 20. The hub 22, on account of the construction 100 of my improved pump, can be made of chilled cast iron and which is permissible in view of the fact that the same can be readily replaced when the requirements of practice so necessitate.

From the foregoing description, it is thought to be obvious that a pump constructed in accordance with my invention is of an extremely simple and comparatively inexpensive nature and is particularly well 110 adapted for use by reason of the convenience and facility with which it may be assembled, and it will also be obvious that my invention is susceptible of some change and modification without material departure 115 from the principles and spirit thereof and for this reason I do not wish to be understood as limiting myself to the precise arrangement and formation of the several parts herein shown in carrying out my invention 120 in practice, except as hereinafter claimed.

I claim:

1. A rotary pump comprising a casing having one side open, a removable head for closing said open side of the casing, a hollow 125 rotor arranged within the casing, a shaft disposed through the casing and the rotor, a side of the rotor being keyed to the shaft, an outstanding annular flange carried by the opposite side of the rotor and concen- 130

- tric to the shaft, an inwardly directed annular flange carried by the removable head of the casing, the flanges of the rotor and the head being concentrically arranged and spaced one from the other, anti-friction means interposed between said flanges, an inwardly directed tubular cam member carried by the head and through which the shaft is disposed, a plurality of blades carried by the rotor and movable inwardly and outwardly with respect thereto, and means coacting with the blades and cam member for imparting the requisite movement to the blades.
- 15 2. A rotary pump comprising a casing having one side open, a removable head for closing said open side of the casing, a hollow rotor arranged within the casing, a shaft disposed through the casing and the rotor, a side of the rotor being keyed to the shaft, an outstanding annular flange carried by the opposite side of the rotor and concentric to the shaft, an inwardly directed annular flange carried by the removable head of the casing, the flanges of the rotor and the head being concentrically arranged and spaced one from the other, anti-friction means interposed between said flanges, an inwardly directed tubular cam member carried by the head and through which the shaft is disposed, a plurality of blades carried by the rotor and movable inwardly and outwardly with respect thereto, and means coacting with the blades and cam member for imparting the requisite movement to the blades.
- 20 3. A rotary pump comprising a casing having one side open, a removable head for closing said open side of the casing, a hollow rotor arranged within the casing, a shaft disposed through the casing and the rotor, a side of the rotor being keyed to the shaft, an outstanding annular flange carried by the opposite side of the rotor and concentric to the shaft, an inwardly directed annular flange carried by the removable head of the casing, the flanges of the rotor and the head being concentrically arranged, an inwardly directed tubular cam member carried by the head and through which the shaft is disposed, a plurality of blades carried by the rotor and movable inwardly and outwardly with respect thereto, and means coacting with the blades and cam member for imparting the requisite movement to the blades, said cam member being detachably engaged with the inwardly directed flange of the removable head of the casing.
- 25 4. A rotary pump comprising a casing having one side open, a removable head for closing said open side of the casing, a hollow rotor arranged within the casing, a shaft disposed through the casing and the rotor, a side of the rotor being keyed to the shaft, an outstanding annular flange carried by the opposite side of the rotor and concentric to the shaft, an inwardly directed annular flange carried by the removable head of the casing, the flanges of the rotor and the head being concentrically arranged, an inwardly directed tubular cam member carried by the head and through which the shaft is disposed, a plurality of blades carried by the rotor and movable inwardly and outwardly with respect thereto, and means coacting with the blades and cam member for imparting the requisite movement to the blades, said cam member being detachably engaged with the inwardly directed flange of the removable head of the casing.
- 30 5. A rotary pump comprising a casing having one side open, a removable head for closing said open side of the casing, a hollow rotor arranged within the casing, a shaft disposed through the casing and the rotor, a side of the rotor being keyed to the shaft, an outstanding annular flange carried by the opposite side of the rotor and concentric to the shaft, an inwardly directed annular flange carried by the removable head of the casing, the flanges of the rotor and the head being concentrically arranged, an inwardly directed tubular cam member carried by the head and through which the shaft is disposed, a plurality of blades carried by the rotor and movable inwardly and outwardly with respect thereto, and means coacting with the blades and cam member for imparting the requisite movement to the blades, said cam member being detachably engaged with the inwardly directed flange of the removable head of the casing.
- 35 6. A rotary pump comprising a casing having one side open, a removable head for closing said open side of the casing, a hollow rotor arranged within the casing, a shaft disposed through the casing and the rotor, a side of the rotor being keyed to the shaft, an outstanding annular flange carried by the opposite side of the rotor and concentric to the shaft, an inwardly directed annular flange carried by the removable head of the casing, the flanges of the rotor and the head being concentrically arranged, an inwardly directed tubular cam member carried by the head and through which the shaft is disposed, a plurality of blades carried by the rotor and movable inwardly and outwardly with respect thereto, and means coacting with the blades and cam member for imparting the requisite movement to the blades, said cam member being detachably engaged with the inwardly directed flange of the removable head of the casing.
- 40 7. A rotary pump comprising a casing having one side open, a removable head for closing said open side of the casing, a hollow rotor arranged within the casing, a shaft disposed through the casing and the rotor, a side of the rotor being keyed to the shaft, an outstanding annular flange carried by the opposite side of the rotor and concentric to the shaft, an inwardly directed annular flange carried by the removable head of the casing, the flanges of the rotor and the head being concentrically arranged, an inwardly directed tubular cam member carried by the head and through which the shaft is disposed, a plurality of blades carried by the rotor and movable inwardly and outwardly with respect thereto, and means coacting with the blades and cam member for imparting the requisite movement to the blades, said cam member being detachably engaged with the inwardly directed flange of the removable head of the casing.

In testimony whereof I hereunto affix my signature in the presence of witnesses.
